UNITED STATES PATENT OFFICE.

FRANK HILLE, OF LONG ISLAND CITY, NEW YORK.

DESIGN FOR AN ASH-TRAY AND MATCH-PICKER.

54,623.

Specification for Design.

Patented Mar. 9, 1920.

Application filed May 31, 1919. Serial No. 301,087. Term of patent 7 years.

To all whom it may concern:

Be it known that I, FRANK HILLE, a citizen of the United States, residing at Long Island City, in the county of Queens and State of New York, have invented a new, original, and ornamental Design for an Ash-Tray and Match-Picker or the like, of which the following is a specification, reference being had to the accompanying drawing, forming a part thereof.

The figure is a perspective view of my ash tray and match picker, showing my new design.

I claim:

The ornamental design for an ash tray and match picker, or the like, as shown.

FRANK HILLE.
